GUIDED MISSILE

John V. Sigford, Los Angeles, Calif., assignor to Minneapolis-Honeywell Regulator Company, Minneapolis, Minn., a corporation of Delaware

Filed June 23, 1959, Ser. No. 56,509

Term of patent 14 years

(Cl. D71—1)

FIG. 1

FIG. 2

FIG 3

FIGURE 1 is a side elevational view of a guided missile embodying my new design;

FIGURE 2 is a side elevational view taken from the right of FIGURE 1.

FIGURE 3 is a perspective view, on an enlarged scale taken from the bottom and left of FIGURE 1.

My design for a guided missile is characterized by the particular stabilizing fins and control vanes, all as shown.

I claim:

The ornamental design for a guided missile, substantially as shown and described.
